UNITED STATES PATENT OFFICE

2,399,166

CUTTER CHAIN

John R. Cartlidge, Cincinnati, Ohio, assignor to
 The Cincinnati Mine Machinery Company,
 Cincinnati, Ohio, a corporation of Ohio

Application January 18, 1943, Serial No. 472,691

2 Claims. (Cl. 74—251)

My invention relates to cutter chains for mining machines and particularly to the pintle means for fastening the same which joins the bit carrying link to the connecting links.

Inasmuch as cutter chains of the above type are subject to very heavy and rough wear, it has been found advisable to position the pintles in the side bars of the bit carrying link so that they will not revolve. This type of pintle and the manner of retaining it in position are disclosed and described in United States Letters Patent 2,280,502, issued April 21, 1942, to Edwin P. Stenger.

It is an object of my invention to provide a pintle retainer for use with a non-revolving pintle, such as described in the above patent, and which prevents the pintle from endwise or longitudinal movement after it has once been placed in position.

It is a further object of my invention to provide such a pintle and retainer wherein the retainer completely seals the pintle in position and thus prevents the entry of moisture with its resulting tendency to etch away any part of the pintle and permit it to slip out.

These and other objects of my invention, which will be set forth hereinafter or will be apparent to one skilled in the art upon reading these specifications, I accomplish by that certain construction and arrangement of parts, of which I shall now describe an exemplary embodiment. Reference is made to the drawing which forms a part thereof and in which:

Figure 1 is a side elevation of a cutter chain including a bit carrying link and connecting links.

Figure 2 is a perspective view of the pintle shown in Figure 1 and before being placed in position.

Figure 3 is a cross-section of the cutter chain and a link with my pintle and pintle retainer in position, taken on line 3—3 of Figure 1.

Figure 4 is a section on line 4—4 of Figure 3 through the link, pintle and cast pintle retainer.

Figure 5 is a plan view of my pintle before the retainer has been cast therein.

Figure 6 is a perspective view of a cast pintle retainer.

Briefly, in the practice of my invention I provide a pintle having such a cross-section that it will not revolve or turn in the spaced side bars of the bit carrying link and as exemplified by the pintle in the above referred to Patent 2,280,502.

In order to prevent my pintle from sliding longitudinally out of the apertures in the side

bars, I have provided a channel longitudinally in the side of the pintle which does not receive active wear, and I provide a countersunk hollow or bevel at the ends of this channel as well as one or more indentures within the channel. The portion of the apertures within the side bars registering with the bevel at the ends of the channel in the pintle is also beveled in a somewhat similar manner as that shown in Figures 1 and 2 of Patent 2,280,502.

The pintle is inserted in place in a similar manner as shown in Patent 2,280,502 and then an alloy, having a relatively low melting temperature, is poured into the space formed by the channel of the pintle and the edge of the apertures in the side bars. From this it is apparent that since the aperture in the connecting link is circular, that the complete space between the pintle and the apertures in the side bars and the connecting link will be filled with this alloy. When the alloy hardens, it is apparent that the cast retainer will fill the indentures in the channel as well as the space between the pintle and the circular aperture in the link, which will prevent longitudinal movement of the retainer as well as of the pintle. Also, the head formed on the retainer by reason of the beveled portions of the channel will assist in preventing longitudinal movement of the retainer and the pintle.

I do not wish to be limited to any specific form of cast retainer or any specific configuration of the pintle, since it is apparent that numerous different shapes may be used, and it is only necessary to have apertures or cut-outs which, when filled with cast metal after the pintle has been placed in position, will prevent its longitudinal movement.

Referring to the drawing, I provide as an exemplary embodiment a pintle 4 having a channel 6 cut therein on its flattened face 5. I also provide indentations 10 within the channel as can be clearly seen in Figures 2 and 5. The ends of the channel 6 are beveled as at 12 and the shoulder 8 of the side bar aperture contains a registering beveled portion 11.

As seen from Figure 3, as well as Figure 1, the pintle 4 is inserted through the apertures 7 in the side bars 2 and through the circular aperture 13 in the connecting link 3.

Any alloy or Babbitt metal having a melting point sufficiently low as to prevent changing the temper in the machined parts may be used. As an example, Babbitt metal having a melting point of 500° F. has been used successfully. The al-

loy may be melted in a ladle and poured in through the channel 6 and allowed to freeze in position, or bars of the metal may be melted by means of a heating torch and permitted to drip into position. It is apparent from the above description, as well as from the drawing, that when the alloy has frozen, a retainer is cast which prevents the longitudinal or endwise movement of the pintle 4, but permits the circular aperture 13 of the link 3 to rotate freely around the pintle 4. It is also apparent that the portion 14 of the cast retainer which consists of frozen alloy is so positioned in reference to the circular aperture 13 that it is not positioned on the active wearing surface of the bearing or pintle.

In order to remove a pintle, it is necessary merely to drive the pintle on through with a sledge hammer. This, of course, shears portions of the cast retainer, which are relatively soft, and permits easy removal. A new pintle is then put in place and a new retainer poured.

As will be apparent, it is possible to place a channel on different portions of the pintle. It is even possible to drill a channel through the pintle and have branches communicating with the space between the circular aperture 13 to the connecting link 3 and the pintle 4. It is also possible to use a channel which does not go completely through the pintle, but merely communicates with one end thereof and a closed aperture between the side bars so that the pintle, the bearing surface of the connecting link, and the side bars will form a mold for the retainer.

I have found that my novel retainer safely holds the pintle against endwise movement, and safely retains it in position at all times during the operation of the cutter chain. I have also found that the use of a relatively soft alloy seals the channel and prevents excessive etching of the cast retainer due to the acids in the water contained within a mine shaft.

It is to be understood that modifications may be made in my invention without departing from the spirit thereof and I do not intend to limit myself otherwise than in the claims which follow.

Having thus described my invention, what I claim as new and desire to secure by Letters Patent is:

1. In a mining machine cutter chain, a bit carrying link having spaced side bars permanently held in position between which a connecting link is introduced, said side bars having aligned segmental shaped apertures and said connecting link having a circular aperture, a pintle having a segmental cross-section positioned within said aperture, means for preventing longitudinal movement of said pintle which comprises a longitudinal channel in the flat surface of the pintle defined by the chord of the segment, pockets in the pintle communicating with said channel and alloy metal within said channel, pockets and said circular aperture unfilled by said pintle.

2. In a chain or the like, relatively pivoted structures, one comprising a perforated link, and the other a pair of perforated bars, one lying on each side of the link with the perforations of the several elements in alignment, a pintle extending through the said perforations and pivoting the structures, said pintle being cut away at one side, and a pintle retaining member in the form of a cast-in-place structure of relatively lower melting point metal extending through said perforations with said pintle, and having such engagement with said pintle and said bars as to prevent relative longitudinal movement of said pintle retaining member, and said pintle having at least one recess extending inwardly toward its center from the cut-away portion, said pintle retaining member also filling said recess.

JOHN R. CARTLIDGE.
